HEAT EXCHANGER

John Forster Alcock, North Lancing, England, assignor to Harry Ralph Ricardo, London, England

Application December 5, 1947, Serial No. 789,997
In Great Britain December 5, 1948

5 Claims. (Cl. 257—6)

1

This invention relates to heat exchangers of the regenerative type in which there is a rotatable member having a matrix of heat-conductive material which is subdivided into cells and traversed by two fluid streams which are caused to flow alternately through the matrix. One of these streams imparts heat to the matrix while the other fluid stream abstracts heat therefrom, the rotation of the matrix positioning each portion thereof in succession so that it will be traversed alternately by the two fluid streams.

Hitherto this type of regenerator has been used in cases where the pressures of the two fluid streams differ little if at all, and consequently it has been fairly easy to minimise leakage from one stream to the other as for instance by employing relatively simple means for sealing the structure. In a gas turbine plant however wherein the exhaust gases from the turbine are used to heat the cold gas delivered by a compressor, and also in other apparatus such as an oxygen producing plant, the pressures of fluids in the two streams passed through the heat exchanger may be very different and more effective methods of sealing become necessary.

The object of the present invention is to provide a particular construction and arrangement in which there is a large flow cross section in a given bulk of the improved form of heat exchanger of the above type which is described in the specification accompanying the application for United States patent Serial No. 727,194, now Patent No. 2,469,758, standing in the name of the present applicant.

In this improved type of heat exchanger there are comprised the following features in combination. There is an annular matrix rotor, a toroidal casing in which the rotor fits and is rotatably mounted, a plurality of disc-like partitions which being spaced apart circumferentially divide the matrix into cells or sections these partitions extending across the matrix and the interior of the casing in a radial direction relatively to the axis about which the matrix is rotatable, two openings through each wall of the casing disposed diametrically opposite or nearly so with respect to the axis of the apparatus and the openings in one wall lying opposite to the openings in the other wall, these openings serving respectively for the inflow and outflow of the two fluids which pass alternately across and through the matrix as the cells therein are successively positioned opposite these openings while the matrix rotates, and tunnel-shaped passages running circumferentially within the contour of the matrix rotor

2

and around the cells therein with the partitions extending across these passages. Preferably the partitions between the cells in the matrix rotor carry spring rings resembling piston rings which constitute seals preventing fluid flow circumferentially between the fluid streams passing through the matrix. Conveniently for the purpose of imparting rotation to the matrix rotor it carries an annular toothed rack which lies in a plane normal to the axis of the rotor and at least two toothed pinions lie in the same plane and mesh with this rack and being driven impart rotation to the rotor. These pinions are geared together and each has a part which is cut away so as to clear the partitions as they pass while enabling the driving of the rotor to be maintained.

The cross-section of the toroidal casing and the corresponding contour of the matrix rotor is preferably circular as being convenient for manufacture, but it may be elliptical or have some other similar shape which is a smooth continuous curve adapted to be sealed by discs and rings in the manner described.

25 Rotation may be imparted to the matrix rotor in various ways from a suitable source of power. For example where the heat exchanger is used in conjunction with a gas turbine rotation may be transmitted to the pinions mentioned above through reduction gearing from the turbine shaft. The rotation of the matrix rotor may be continuous or intermittent as may be suitable in the apparatus in which the heat exchanger is employed.

35 According to this invention the construction comprises in combination two or more rotors each constituted by an annular matrix rotatable in a toroidal casing and constructed and arranged as indicated above, the rotors being all mounted on a common axis and either coaxially or concentrically, means for simultaneously rotating all the rotors, and an outer casing enclosing all the rotors and their individual casings and provided with passages through which the hot and cold gases can respectively flow and be caused to pass through all the rotors in opposite directions.

45 If the rotors are disposed coaxially they may have the same or different diameters and they may be arranged respectively to lie in planes which are spaced apart equally or otherwise in the axial direction. On the other hand rotors having different diameters may be disposed concentrically. The enclosing casing and the gas passages therein may be arranged in various ways

in accordance with the disposition of the several rotors.

The accompanying drawings illustrate somewhat diagrammatically alternative constructions that may be used in carrying the invention into practice. In these drawings,

Figure 1 is a longitudinal sectional elevation of a construction of the improved heat exchanger in which there are three matrix rotors disposed coaxially.

Figure 2 is a similar view in which there are three matrix rotors disposed concentrically.

Figure 3 is a part section on the line 3—3 in Figure 2 looking in the direction of the arrows.

Figure 4 is a similar view to Figure 1 of a further alternative construction.

Referring to Figure 1 it will be seen that the three separate annular rotors A, B, and C all have different diameters and are arranged in separate toroidal casings D, E and F. It will be perceived that each of these casings defines a true toro or torus, since its surface may be formed by rotating a conic section (in this case a circle) about a straight line lying in the plane of the curve of the circle but not intersecting the circle and it is in this sense that the word "toroidal" is employed herein. The several rotors may be conveniently designated as A the smallest, B of intermediate size and C the largest in diameter with respect to their common axis. Conveniently as shown the toroidal enclosures or casings D, E and F containing the rotors A, B and C, are all circular in cross-section and these sections are all similar in size. The rotors are all mounted about a common axis and driven so that they will be rotated together being preferably equally spaced apart in the axial direction. All the rotors are disposed within a common casing G in which is a central partition G¹ about which the rotors turn. Within the casing G are twin passages on each side of the partition G¹, H is the intake to one passage whose outlet is at H¹, the second passage having its inlet at J and its outlet at J¹. Extending across each of these passages is a partition, namely K, in the passages HH¹ and L in the passage JJ¹. These partitions are relatively inclined so that they appear as seen in Figure 1 as a V-formation. In these partitions are openings K¹L¹ through which the gases pass as they flow through the matrix material in the several rotors. Through these openings can be seen, for example in the case of the rotor C, the partitions C¹ with their sealing rings C² which extend radially across the matrix material C³ and divide it into cells. Between the openings K¹ and L¹ there is a part on each side of the partition G¹ which forms a dead zone behind which the sealing by the partitions C¹ between the matrix cells prevents flow or leakage of gas between the passages HH¹ and JJ¹. The toroidal casings D, E and F within which are the toroidal rotors A, B and C are mounted in these partitions K, L, and the rotors are caused to rotate in their respective casings. The drive is transmitted to the several rotors first through a shaft M which passes out through the casing G and has at its near end a bevel wheel M¹. This wheel meshes with a bevel wheel N on the end of a shaft N¹ which carries spaced apart along its slightly skew gear wheels N², each of which meshes with a corresponding gear wheel O on a shaft O¹. This shaft has on it spaced apart three gear wheels O² through which the drive is transmitted to toothed racks carried by the rotors A, B and C.

A gas entering the casing G through the inlet

J will pass through all the rotor matrices A, B and C and issue at J¹, heat being given up to the several matrix bodies in the rotors. A second gas entering the casing G at H will pass through the matrix rotors A, B and C in the reverse direction and issue from the outlet H¹, the gas having taken up in its passage heat from the rotor matrices, this heat as stated having been imparted thereto by the gas flowing through the passage HH¹.

In this construction the gases in flowing through the passages in the casing G will pass in a substantially radial direction through the several rotors.

The gear wheels on the shaft O¹ through which the racks on the rotors are driven differ in diameter, an arrangement which ensures that the several rotors A, B and C are driven at substantially the same speed.

The outer casing G which encloses all the rotors may have a generally cylindrical external form with the twin openings H and J¹ for the flow of gases at one end and the twin openings H¹ and J at the other end.

In some cases all the rotors A, B and C and their individual casings D, E and F may have the same diameter and they may then be spaced apart along their common axis so that the casing structure G in which the rotors are enclosed and move may have a generally cylindrical formation. The gas flow through the rotor matrices will then be in a positively radial direction.

Figure 2 shows an alternative construction wherein the rotors A¹, B¹ and C¹ differ in diameter and are placed with their toroidal casings D¹, E¹ and F¹ concentrically about their common axis. In this case the gas flow is shown as taking place through twin passages which are distinct, being constituted by separate casings suitably connected, the one casing comprising the connected parts P, Q and the other casing comprising the connected parts P¹, Q¹. The passage P² in the casing P is that through which the gas enters to flow through the rotors in one direction, issuing through the passage Q² in the casing Q. The flow in the opposite direction enters the casing Q¹ through the passage Q³ and issues through the passage P³ in the casing P¹.

The rotors are separately driven in this case in the same way as in the construction shown in Figure 1, that is to say the drive is initially transmitted through a gear wheel on the end of a shaft N¹ which carries three gear wheels N² respectively meshing with gear wheels O on a shaft O¹ which in turn carries gear wheels through which the racks on the rotors are driven in a way to be described hereunder.

Such an arrangement as that illustrated in Figure 2 may be used to make up a multi-rotor in which there may be two or more heat exchanger units as shown in Figure 2 mounted adjacent with the rotors all suitably and simultaneously driven. The gas flows will then take place in succession through the rotors in all the units in opposite directions in the same way as described with respect to Figure 2.

While for reasons of constructional simplicity it may be desirable to make all the rotors similar with respect to the size of the annular matrices and their toroidal casings as seen in cross-section, on the other hand in some cases it may be useful to give associated rotors different cross-sectional dimensions.

The transmission from the gear wheels on the shafts O¹ to the rotors in each of the above de-

scribed constructions is effected in the same way as in the apparatus described in the specification of the above-mentioned United States Patent No. 2,469,758. This transmission is shown in Figure 3 in the present drawings. Each rotor carries a toothed rack R which extends round the periphery of the rotor, the continuity of each of these racks being interrupted by partitions in the rotors the partitions extending transversely across the matrix material in the rotors. Meshing with this rack are two toothed pinions S and T, rotatably mounted and preferably enclosed. These pinions lie in the same plane, and they are spaced apart along the rack. Each pinion has a part S¹T¹ cut away so as to allow the pinion as it rotates to clear each partition U in a rotor. Each mutilated pinion S¹ and T¹ carries a similar pinion S²T² and both these pinions mesh with a gear wheel O² on the shaft O¹. The pinions S and T are thus simultaneously driven and are at such a distance apart, and have their cut away parts S¹T¹ arranged in such rotational relationship that as the pinions are driven and in turn rotate the rack R, continuity will be maintained in the transmission to the matrix rotor. When the cut away part T¹ of the pinion T is clearing a partition U it will be seen that the other pinion S will be still in engagement with the rack R and maintaining rotation of the matrix rotor.

In the construction shown in Figure 4 the arrangement is generally similar to that shown in Figure 1 except that the dimensions of the three rotors and their associated parts are the same. Thus in the construction shown in Figure 4 the rotors A², B², C² correspond to the rotors A, B and C of Figure 1, the toroidal casings D², E², F² correspond to the casings D, E and F of Figure 1, while the casing G² corresponds to the casing G in Figure 1 and contains passages on each side of a partition G³ constituting intake and out-take passages H², H³ and intake and out-take passages J², J³ correspond to the passages H, H¹ and J, J¹ of the construction shown in Figure 1. The various rotors are driven by gears M², N², a shaft N⁴ and gears N⁵ in a manner generally similar to that employed for driving the rotors in the construction shown in Figure 1, the duplex gearing as shown in Figure 3, however, not being visible in Figure 4.

What I claim as my invention and desire to secure by Letters Patent is:

1. A heating exchanger of the regenerative

type comprising in combination a plurality of rotors each constituted by an annular gas-pervious matrix of heat-conducting material, and radial partitions subdividing the material into cells, a plurality of toroidal casings, each annular matrix being supported for rotation in one of said toroidal casings, an outer casing enclosing said rotors, means mounting said rotors in said outer casing for rotation about a common axis, means for rotating all the rotors simultaneously, said outer casing being constructed to provide a pair of passages defining separate fluid paths, means forming with said toroidal casings a partition extending across each of said passages, each partition being formed with openings to permit flow of fluid in each path through said rotors, and means whereby two separate fluids are caused to flow in opposite directions through the said passages, whereby on rotation of said rotors each fluid will flow through all the cells in each rotor as these cells are positioned in succession in the fluid paths.

2. A heat exchanger embodying the features as set out in claim 1 in which the several rotors are disposed so that they are coaxial and lie adjacent in planes spaced apart in the axial direction.

3. A heat exchanger embodying the features as set out in claim 1 in which the rotors have different diameters and are disposed so that they are coaxial and lie adjacent in planes spaced apart in the axial direction.

4. A heat exchanger embodying the features as set out in claim 1 in which the rotors have all the same diameter and are disposed so that they are coaxial and lie adjacent in planes spaced apart in the axial direction.

5. A heat exchanger embodying the features as set out in claim 1 in which the rotors have different diameters and are disposed so that they are all concentric.
